UNITED STATES PATENT OFFICE

2,490,443

FILTER

Louis H. Knipper, Dayton, Ky.

Application April 13, 1945, Serial No. 588,118

1 Claim. (Cl. 210—94)

1

This invention relates to a filter, one that can operate in a horizontal or vertical position direction independently and can be used with pumps and other similar types of machinery used with water, oil, or other liquids.

An object of the invention is to provide a device that avoids clogging of the device as well as preventing foreign objects from passing into the pumps and causing wear on vital parts.

Another object of the invention is to provide a device that will operate from the top thereof while the bottom remains inactive.

A further object of the invention is to provide a device that is inexpensive to manufacture, easy to assemble, and efficient in operation.

With these and other objects and advantages in view the invention comprises certain novel combinations, constructions and arrangements of parts as will be hereinafter described, illustrated in the accompanying drawings and more particularly pointed out in the appended claim.

In the drawings:

Fig. 1 is a side elevation of an embodiment of the invention.

Fig. 2 is an end view thereof.

Fig. 3 is a sectional view on the line 3—3 of Fig. 1.

Fig. 4 is a modification of the coupling means of the device.

Fig. 5 is a sectional view thereof.

Fig. 6 is a detailed view of the screen holding rod.

Fig. 7 is an end view thereof.

Fig. 8 is a sectional view on the line 8—8 of Fig. 5 and.

Fig. 9 is a sectional view on the line 9—9 of Fig. 5.

Referring more in detail to the drawings the numeral 10 designates the tubular casing or body of the filter which can be made of sheet metal, bar stock, or a suitable thermosetting plastic, as stated the body 10 is tubular open at the end 12 and closed at the end 14.

In Fig. 1, the open end 12 is externally threaded for the reception of a pump suction tube, or for connection to any other type of machinery with which the filter is to be used.

The casing 10 is provided near the threaded portion of the end 12 with a shoulder 16 that can be round, square, or hexagonal for the reception of a wrench or other tool for the purpose of tightening the filter when connections are being made.

One side of the casing 10 is provided with perforations or openings 18.

2

These openings 18 act as intakes for the liquid to be filtered and can be set in any position to suit the conditions of the liquid and the foreign objects involved.

5 The openings are positioned in parallel rows and in relatively spaced staggered relation to each other.

A circular mesh screen 20 having the ends thereof cleated in circular collars 22 is positioned 10 on the casing 10 and is retained thereon by means of screws 24. The mesh perforations can be of a size suitable to the conditions existing at the time the filter is to be used.

The screen 20 is of a sufficient length to entirely 15 cover the rows of openings 18 in the casing 10.

A circular inner mesh screen 26 having a rounded nose or end 28 and an open end 29 is positioned in the casing 10. This screen is preferably made of brass, but can be made of any 20 other non-corrosive material, and perforations in this screen will be of a size suitable for the prevailing conditions at the time the filter is to be used.

The diameter of the screen 26 is of a slightly 25 smaller diameter than the internal diameter of the casing 10 thus permitting sufficient space between the screen 26 and casing 10 to prevent clogging of the screen.

The screen 26 is retained in position in the 30 casing 10 by means of a circular band or collar 30 which is secured to the open end 29 of the screen 26 and a rod 32.

The band 30 has an outer circumference of a sufficient diameter to slidably fit in the inner 35 circumference of the casing 10.

The rod 32 has a head 34 positioned within 40 and conforming to the rounded end 28 and passes through an opening 36 provided in the end 28 of the screen 26. The rod 32 passes through an opening 38 in the closed end 14 of the casing 10.

The end of the rod is threaded and extends 45 beyond the end of the casing 10 to receive a complementary threaded nut 40. In this fashion the screen 26 is properly positioned and retained in the casing 10.

The space 41 thus provided by the length of the rod 32 acts as a trap for small foreign objects and will prevent the clogging of the screen 50 26.

In Fig. 4, is disclosed another method of coupling or connecting the filter to the pump or other machinery with which it is to be used.

In this instance the end 12 of the casing is 55 provided with a circular groove 42.

The end 12 is received in the socket or sleeve 44 and is retained therein by a set screw 46 which enters the groove 44 and rotatively retains the casing 10 therein, or if the set screw 46 is sufficiently tightened will retain the casing therein in a fixed or set position.

The socket 44 can be a part of a pump suction tube 48, or can be made in any other fashion such as internally threaded for connecting the socket 44 as desired.

It will be understood, therefore, by those skilled in the art that the embodiment of the invention herein disclosed accomplishes the objects of the invention and provides a device that can be used in a vertical or horizontal position and can use mesh screens having various sizes of perforations to meet the prevailing conditions existing at the time the filter is to be used. It also has other advantages than those herein particularly referred to, also that various changes and modifications may be made without departing from the spirit of the invention or the scope of the appended claim.

Having thus described the invention, what is claimed as new and desired to be secured by Letters Patent is:

A device of the character described comprising a tubular casing having an open end and a closed end and an attaching coupling fitting on the open end, said casing being provided with inlet openings for a substantial portion of its length, an outer circular screen surrounding the outer circumference of the casing for a substantial portion of its length and overlying the inlet openings of said casing, a circular band of a diameter slightly smaller than the inner circumference of said casing slidably fitted in said casing, an inner tubular screen of a diameter slightly smaller than the inner circumference of said band and of a length substantially less than the

length of the casing and having an open end secured to the inner circumference of the band and a closed end directed toward the closed end of the casing whereby the inner tubular screen is slidably mounted in said casing and whereby the space between the inner tubular screen and the casing provides a sediment chamber, and adjustable means in the closed end of the inner tubular screen and extending between the inner tubular screen and the closed end of the casing for retaining said inner tubular screen in position and said means comprises a rod attached to the closed end of the inner tubular screen at one end and having its other end threadably mounted in the closed end of the casing and provided with a lock nut exteriorly of the closed end of the casing.

LOUIS H. KNIPPER.
